UNITED STATES PATENT OFFICE.

JOHN ROBERT CUNNYNGHAM, OF CHATTANOOGA, TENNESSEE.

BAG-FILLING APPARATUS.

1,257,816.

Specification of Letters Patent. Patented Feb. 26, 1918.

Application filed April 14, 1916. Serial No. 91,211.

To all whom it may concern:

Be it known that I, JOHN ROBERT CUNNYNGHAM, a citizen of the United States, residing at Chattanooga, in the county of 5 Hamilton and State of Tennessee, have invented new and useful Improvements in Bag-Filling Apparatus, of which the following is a specification.

This invention relates to improvements in 10 bag filling apparatus and has particular application to a combined cut-off and measuring device.

In carrying out the present invention, it is 15 my purpose to provide a combined cut-off and measuring apparatus for filling bags, sacks and the like whereby a predetermined quantity of material may be delivered to each bag or sack without waste of material and wherein measuring elements of different 20 capacities may be employed so that the apparatus may be used for filling bags of different capacities.

It is also my purpose to improve and simplify the general construction of cut-off and 25 measuring devices and to provide a device of the class described which will embrace the desired features of simplicity, efficiency and durability and which may be manufactured and marketed at minimum expense.

With the above and other objects in view, 30 the invention consists in the construction, combination and arrangement of parts hereinafter set forth in and falling within the scope of the claim.

35 In the accompanying drawings;

Figure 1 is a vertical sectional view through a measuring device constructed in accordance with my present invention.

Fig. 2 is a similar view taken at right 40 angles to Fig. 1.

Fig. 3 is a cross sectional view on the line 3—3 of Fig. 1.

Fig. 4 is a like view on the line 4—4 of Fig. 1.

45 Fig. 5 is a perspective view of a detail of the invention.

Referring now to the drawings in detail, 1 designates a base. Upstanding from the base 1 are standards 2 spaced apart equal 50 distances in square formation. Arranged between the standards 2 at the upper extremities thereof and suitably secured to such extremities is a hopper 3 of any desired capacity designed to contain the material 55 to be measured and delivered to the bag. Arranged below the lower end of

the hopper 3 is a substantially rectangular plate 4 through which the standards 2 pass. Secured to the lower end of the hopper 3 and bearing upon the plate 4 is a 60 channeled guide 5 extending across the plate 4 and formed in the channel guide 5 and the plate 4 are openings alining axially with the outlet opening of the hopper 3. Arranged below the plate 4 is a rectangular 65 plate 6 formed with openings through which the standards 2 pass and capable of sliding movement along the standards. Formed on the upper side of the plate 6 and extending across the same is a channeled guide 7 70 formed with an opening alining axially with the openings in the plate 4 and the hopper and opening into the upper end of a discharge chute 8 secured to the lower side of the plate 6 and depending therefrom. 75 Secured to the under side of the plate 6 adjacent to the respective edges thereof and depending therefrom are supporting arms 9 converging toward each other at their lower ends and secured to the lower ends of 80 the arms 9 is a vertical sleeve 10 slidably mounted upon a vertical rod 11 secured to the base 1. This sleeve 10 is equipped with a set screw 12 whereby the sleeve may be held in adjusted position upon the rod 11. 85 Formed on the lower side of the plate 4 concentrically of the opening therein is an annular flange 13, while formed on the upper surface of the channeled guide 7 is an annular flange 14 alining with the flange 90 13. 15 designates a measuring tube disposed between the plates 4 and 6 and having the upper ends thereof arranged within the flange 13 and the lower end disposed within the flange 14. This measuring tube 95 15 is capable of removal and another measuring tube of a different size may be inserted in its place so that the apparatus may be adjusted to measure various quantities of material.

100 Slidably mounted in the respective channeled guides 5 are slide valves 16 and 17 and formed in the valve 16 is an opening 18, while formed in the valve 17 is an opening 19 arranged at one side of the opening 18 in the valve 16 so that when the opening 18 is in registration with the lower end of the hopper the opening 19 will be out of registration with the lower end of the measuring tube, while when the opening 19 is 110 in registration with the measuring tube the opening 18 will be out of registration with

the discharge end of the hopper. These openings 18 and 19 are so arranged relatively to each other that the valve 16 cuts off communication between the hopper and the measuring tube before communication is established between the measuring tube and the discharge chute 8. One end of each valve is downturned as at 20 so as to limit the sliding movement of the valve in one direction, while connected to the remaining ends of the valve are connectors 21 formed with outwardly projecting vertically alining ears 22. 23 designates a vertical operating bar arranged between the ears 22 and secured thereto by means of pins 23' passed through alining openings in the ears and the bar. This bar 23 is formed with a longitudinal series of openings, as clearly shown in Fig. 1 of the drawings, so that the pins 23' may be passed through the bar after the plate 6 has been adjusted relatively to the plate 4.

In practice, the set screw 12 is loosened and the sleeve 10 moved downwardly along the rod 11 to lower the plate 6 so that the tube 15 may be removed and another tube inserted and when the other tube has been applied the plate 6 is moved upwardly to a position to effectively hold the tube 15 between the plates 4 and 6. The set screw 12 is then tightened in order to hold the plate 6 in adjusted position. Normally, the opening 18 in the valve 16 is in registration with the hopper so that the material poured into the hopper will flow into the tube 15. After the tube 15 has been filled the valves 16 and 17 may be operated by the bar 23 so as to cut off communication between the hopper and the measuring tube and establish communication between the measuring tube and the chute 8 whereby the material contained in the measuring tube may be discharged into a bag held at the lower end of the tube 8.

45 By means of the adjustable connections between the valves and the operating bar 23, the bar 23 may be properly connected to the valves after the tube 15 of the desired

size has been secured in place between the plates 4 and 6.

While I have herein shown and described one preferred form of my invention by way of illustration, I wish it to be understood that I do not limit or confine myself to the precise details of construction herein described and delineated, as modification and variation may be made within the scope of the claim and without departing from the spirit of the invention.

I claim:

A cut-off and measuring device for filling bags and the like embodying spaced vertical standards, a hopper secured to the upper ends of said standards, a plate arranged below said hopper, a channeled guide formed with the lower end of said hopper extending across said plate and formed with an opening alining with the outlet end of said hopper and with an opening in the plate, an annular flange formed on the lower surface of the plate and concentrically of its opening, a second plate having an opening vertically alining with the opening of the first mentioned plate and channeled guide, an annular flange formed on the upper surface of the second mentioned plate and concentrically of its opening, a discharge chute leading from the opening of the second mentioned plate, a measuring tube interposed between the hopper and discharge chute with the ends thereof engaging in the annular flanges, valves slidably mounted in said guides, supporting arms depending from the last named plate, and means carried by the said arms for effecting a vertical adjustment of the last mentioned plate in a direction toward or from the first mentioned plate to accommodate measuring tubes of various sizes to be interfitted between the hopper and discharge chute.

In testimony whereof I affix my signature in presence of two witnesses.

JOHN ROBERT CUNNYNGHAM.

Witnesses:

W. M. PROPER,

CARL HUNT.
